(57) **CLAIM**

The ornamental design for a fire pit, as shown and described.

DESCRIPTION

FIG. 1 is a perspective view of a fire pit showing our new design with the legs in a first position.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a section view taken along line 8-8 of FIG. 6.

FIG. 9 is a perspective view of the fire pit with the legs in a second position.

FIG. 10 is a front elevation view thereof.

FIG. 11 is a rear elevation view thereof.

FIG. 12 is a left side elevation view thereof.

FIG. 13 is a right side elevation view thereof.

FIG. 14 is a top plan view thereof.

FIG. 15 is a perspective view of the fire pit with the legs in a third position.

FIG. 16 is a front elevation view thereof.

FIG. 17 is a rear elevation view thereof.

FIG. 18 is a left side elevation view thereof.

FIG. 19 is a right side elevation view thereof; and,

FIG. 20 is a top plan view thereof.

The dashed lines shown in the drawings are for purposes of illustrating portions of the article that form no part of the claimed design.
